AUTOMATIC STEAM HEATING SYSTEM FOR
AUTOMOBILES

James B. Moncrief, Copperhill, Tenn.

Application February 16, 1938, Serial No. 190,749

17 Claims. (Cl. 237—12.3)

My invention relates to a steam heating system for automobiles and is characterized by the provision of automatic controls for the generation of steam under vacuum in the heating system and for the control of the radiator fan or blower so that it remains inactive when the radiator is cold or the system is taking in water.

More particularly, my invention contemplates the provision of a water jacket fitted to the exhaust line and designed efficiently to vaporize water by the heat from the automatic engine exhaust, with thermal bulbs or thermostatic agencies so arranged and coordinated with the heating system and with expansible bellows, or the like control elements, that when there is demand for water in the system they will introduce it in quantity sufficient to supply steam throughout the heating system, said controls holding a vacuum always on the heating system while operating and acting automatically to open and close the controls for the blower motor responsive to the presence or absence of the steam in the heating system.

My invention further contemplates the provision of differentially operated bellows controls which coat to supply the system with water and which maintain its water supply valve always closed when such controls are in balanced relation, means being provided so to regulate the differential action of these controls that when they become unbalanced the water supply valve will open and admit water at times and in quantities definitely and accurately controlled by predetermined temperature conditions in different parts of the heating system.

My invention further contemplates utilizing a control element for the water supply valve to close a starter switch for the heater fan motor responsive to the presence of steam in the system, so that the motor will run only when the radiator can heat the fan-induced air current flowing therethrough.

The invention also contemplates the application of one or more such heating systems, according to the capacity of the automobile to be heated, and comprises various novel details of construction and arrangements of parts which, in their preferred embodiments only, are illustrated in the accompanying drawing, in which:—

Fig. 1 is a schematic layout of my improved heating system with the control parts shown in the position they will occupy when the heating system is cold.

Fig. 2 is a cross-sectional view taken on the line II—II of Fig. 1.

Fig. 3 is a cross-sectional view taken on the line III—III of Fig. 1.

Fig. 4 is a modification of the thermal bulb control for the water supply and vacuum control valves.

Similar reference numerals refer to similar parts throughout the drawing.

In the embodiment of my invention illustrated, I show conventionally an intake manifold 5, an exhaust manifold 6, and an exhaust pipe 7, for any standard automobile engine, not shown, which parts may have any conventional arrangement in the automobile.

I mount at some convenient point on the exhaust pipe 7, an arcuate steam generator 8 having, as shown in Fig. 3, a relatively small capacity and so large a surface area in contact with the pipe 7, that I obtain an efficient transfer of heat thereto and a "flash" generation of steam. A suitable clamp 9 is applied about the generator 8 and pipe 7 to hold them fixedly in assembled relation and the generator is supplied with a suitable safety blow-off valve 10 and a steam pipe 11 which leads from its upper end and is connected by a flexible hose or like element 12 to an intake nipple in the bottom of a steam chamber 13. This chamber is spaced from the generator and is shown mounted under the bottom flange 15 of a steel plate frame 14 that may be mounted at any suitable point in the automobile. From chamber 13 a steam pipe 16 leads up through the lower and upper flanges 15 and 17 of the plate frame and is suitably connected by rigid or flexible piping 18 to a conventional steam radiator 19, such as is in common use for heating automobiles.

Air is forced through this heater and into the automobile by a fan 20 driven by an electric motor 21 which has appropriate circuits 22 and 23, with an automatic switch 24 interposed in the ground lead. The switch 24 is shown mounted on an insulation block on the top flange 17 and may be of any conventional type. A manual control switch 25 in a motor lead, placed at any convenient point is adapted to regulate the motor speed and to cut it out of service independently of its automatic control.

A small suction pipe line 26 leads from the manifold 5 downwardly through the frame flanges 17 and 15 and enters the steam chamber 13, and a valve 27 is mounted in this line between said flanges. When this valve is open and the engine running a vacuum in the steam system is quickly established and exists as a normal condition under which the system operates.

A small water supply pipe line 28 leads from

the cooling system, not shown, or any other available source of supply and also passes downwardly through the frame flanges and is connected to the lower end of the steam generator 8. In this line 5 is a manual cut off valve 29 and an automatic water supply valve 30 that is disposed between said flanges.

I mount on the lower frame flange 15 a bellows 31, or like expansive element, for controlling the vacuum valve 27, and a pair of similar bellows 32 and 33 for jointly controlling the water supply valve 30.

The bellows 31 is connected by a pipe 34 in closed circuit to a thermal bulb 35 fixedly mounted 15 in any suitable manner in contact with, or in position to be heated by, the steam generator or the exhaust pipe 7 so that it will respond to any appreciable rise in temperature therein. This bulb, its pipe 34 and its bellows 31 are filled in a 20 closed circuit with any suitable expansible fluid or gas, which in response to predetermined rise in the thermal bulb temperature will cause the bellows 31 to expand. This bellows actuates a stem 36 that extends through and is guided by the 25 frame flange 17 and has a pair of spaced lugs 37 between which the stem for the vacuum valve 27 is closely engaged. Above these lugs the stem 36 is threaded to receive an adjusting nut 38 which controls the position of a washer 39 forming 30 a seat between which and the flange 17 I mount a coiled spring 40, the tension on which is adjusted to control the temperature required to cause the thermal bulb 35 to expand the bellows 31 and move the stem sufficiently to close 35 the vacuum line valve 27. When the bellows 31 contracts, the spring assists in opening the valve 27. When the valve is open and the motor is running a vacuum will be promptly established throughout the heating system. The vacuum 40 connection 26 is so located that condensate cannot enter the automobile engine.

I use a second thermal bulb 41, which is preferably applied to the steam line 11 and through its pipe 42 controls the bellows 32 which also has a 45 stem 36 equipped with a tension spring 40 as above described. The lugs 37 upon this stem of bellows 32 engage between them the left hand end of an arm 43 for operating the water supply valve 30. In like manner a thermal bulb 44, which is mounted in the steam chamber 13, will through its pipe 45 control a bellows 33. This bellows 33 has a special stem 46 that is not equipped with a tension spring and has its lugs 37 so spaced that when the bellows is contracted 50 and the water supply valve stands in closed position against the stop lug 47 on the frame 14, the lower lug will allow the stem 46 to rise before engaging arm 43 sufficiently to close the make-and-break switch 24 and start the fan motor. Provided on the stem 46 is a clearance 55 adjusting nut 50, to vary the time of closing of the switch contact 24.

The water supply valve 30 and the vacuum valve 27 can be of any conventional type adapted 60 when rocked through a predetermined angle in a clockwise direction, as seen in Fig. 4, to open their respective pipe lines, and when rocked back to close said supply line. The detail structure of the valves is immaterial as it may be widely varied 65 to suit any particular needs.

The bellows 31 and 32 are opposed by their respective springs 40 so as to insure their positive return, 31, to open the vacuum valve, and 32, to close the water valve 30. The spring action 70 75 can be delicately adjusted so that the action of

bellows 32 will be timed with relation to the action of bellows 33, which latter bellows requires no counter-balancing spring because its function is to prevent bellows 32 opening valve 30 whenever the system is sufficiently supplied with water. The tension on bellows 32 should be set so that the water supply valve will not open to supply water to the system until the generator has become sufficiently hot to evaporate, instantaneously such water, and the action of the bellows 33 10 which should be so timed as to permit only enough water to enter the generator as will fill the system with steam. On subsequent startings this small amount of water in the system under vacuum will soon be vaporized, and I consider 15 it desirous that the system run on the smallest amount of water possible, which will be periodically and automatically replaced as needed, as in this way I obtain a faster condensation and I am enabled to take better advantage of the latent 20 heat of the steam which is many times as effective as the sensible heat of water.

I charge each thermal bulb 35, 41 and 44 and its respective connection and bellows with some liquid which will vaporize from 30° F. to 50° F. 25 below the vaporizing temperature of the water in the system. The water in the system being under vacuum, will vaporize at less than 212° F., say about 190° F. The bulb charge should have a vaporizing temperature sufficiently high so that its bellows will return to rest whenever the engine cools, even in the warmest weather. Thus, I prefer that the above charge should vaporize about midway between 100° F. and 190° F. As a suitable charge I may use chloroform which vaporizes at approximately 142° F. atmospheric, but it will be understood that the most suitable element for the charge may be selected having in consideration whether the bulb is charged under pressure, at atmospheric, or under vacuum. 30 Water itself can be used if the bulb were charged under sufficient vacuum to cause it to vaporize at about 140° F.

While I have shown separate thermal bulbs 35 and 41 employed, nevertheless my system is effectively operable where a single bulb 35 is used, as shown in Fig. 4, the connections 42 and 34 being led to this same bulb so that as it becomes heated both bellows 31 and 32 will be simultaneously expanded, the one to close the vacuum valve and trap the vacuum in the system, and the other to open the water valve until it becomes counter-balanced by the effect of steam on the thermal bulb 34 to expand bellows 33 and force the return of the water supply valve to 50 closed position.

In operation, assuming the engine cold, no water in the generator 8, valve 29 open, water supply valve 30 closed, vacuum control valve 27 open, and the several bellows contracted.

As the engine starts its first effect will be to exhaust air from the whole heating system, and then its exhaust line will heat up and start heating the generator 8 and thermal bulb 35. This thermal bulb 35, will respond first and cause bellows 31 to expand and close vacuum valve 27, so trapping the vacuum in the system. The thermal bulb 41 will next heat and expand its bellows 32, lifting stem 36 against the action of spring 40 so as to rock the arm 43 into position 60 to open the water supply valve 30 and admit a small quantity of water to enter the steam generator. This generator being then hot will quickly vaporize this water, producing steam which at once takes effect on thermal bulb 44, expanding 65 70 75 80 85 90 95 100

its bellows 33 and causing same to counter-balance the action of bellows 32 on the water valve 30 and, with the assistance of spring 40, to rock arm 43 against stop 47 and shut off the water supply. The vacuum valve 27 will stay closed as long as the engine is warm. Upon subsequent startings there will probably be sufficient water in the generator, in the form of condensation, which is returned thereto, so that this will 10 promptly be vaporized and will heat terminal bulbs 41 and 44 at about the same time whereby they will be caused to oppose each other and prevent the opening of the water supply valve 30, and this balanced condition will continue 15 until there is an inadequate supply of water, whereupon steam will fail to heat the thermal bulb and bulb 41 will be hot enough to expand its bellows 32 the latter will be freed to expand and open the water supply valve.

20 Thus steam will be produced for the radiator in a very short time when needed from the hottest point on the engine, and under a vacuum which is pulled "fresh" each time the engine is started after being cold and which accelerates 25 the vaporization of the water and prevents the heater becoming full of air.

My system will automatically admit water only when needed and then only in whatever amount is required to produce sufficient steam to heat 30 the radiator and effect the controls above set forth and it admits only the make up water which will replace that lost through service.

The safety valve 10 will open in time to prevent damage from high pressure within the system.

It will be understood that the fan will remain idle until the thermal bulb 44 is heated and thus it will not operate except when steam is present in the radiator.

40 As heretofore stated, a number of these systems may be applied at different points on the exhaust pipe and one or more heaters used in the same or different compartments of the vehicle. It will also be apparent that my improved 45 system is not necessarily limited to an automobile heating system, but may be used with equal advantage on any type of heating system embodying a similar problem of heat transfer. It also is not necessarily limited to one in which 50 a partial vacuum is maintained, but may be employed with systems employing superatmospheric pressures.

While I have shown my invention in but two forms, it will be obvious to those skilled in the 55 art that it is not so limited, but is susceptible of various other changes and modifications, without departing from the spirit thereof, and I desire, therefore, that only such limitations shall be placed thereupon as are imposed by the prior 60 art or as are specifically set forth in the appended claims.

What I claim is:—

1. In a heating system for automobiles having an automotive engine comprising an intake manifold and an exhaust line, a steam generator heated by said line, a steam radiator connected to said generator, a valve controlled means having connection with said intake manifold and adapted to establish a vacuum in the heating 70 system, a valve controlled means to supply water to said system, means automatically responsive to heat from the exhaust line to control the supply of water thereto, and means responsive to the presence of steam in the system to cut 75 off said water supply.

2. In a heating system for automobiles having an automotive engine comprising an intake manifold and an exhaust line, a steam generator heated by said line, a steam radiator connected to said generator, a valve controlled means having connection with said intake manifold and adapted to establish a vacuum in the heating system, a valve controlled means to supply water to said system, and counter-acting agencies which control said water supply valve, one responsive to exhaust line heat to open the valve and the other responsive to steam heat in the system, to close the valve.

3. In a heating system for automobiles having an automotive engine comprising an intake 15 manifold and an exhaust line, a steam generator heated by said line, a steam radiator connected to said generator, a valve controlled means having connection with said intake manifold and adapted to establish a vacuum in the heating system, a valve controlled means to supply water to said system, and counter-acting agencies which control said water supply valve, one responsive to exhaust line heat to open the valve and the other responsive to steam heat in the 20 system, to close the valve, the latter being adapted to prevail and prevent the admission of water while steam is available for said radiator.

4. In a heating system for automobiles having an automotive engine comprising an intake 30 manifold and an exhaust line, a steam generator heated by said line, a steam radiator connected to said generator, a valve controlled means having connection with said intake manifold and adapted to establish a vacuum in the heating system, a valve controlled means to supply water to said system, means automatically responsive to heat from the exhaust line to control the supply of water thereto, means responsive to the presence of steam in the system to cut off said 40 water supply, and means for closing said connection to the intake manifold only while the heating system is working.

5. In an automobile heating system, in combination, an automotive engine comprising an intake manifold and an exhaust line, a steam generator heated by said line, a steam radiator supplied with steam by said generator, a valve controlled means having a connection to said intake manifold and adapted to establish a vacuum in said system, means responsive to heat in said generator to close said valve when the system is hot, a valve and means controlled thereby to supply water to said generator, two coordinated 55 agencies responsive to the generator heat for jointly controlling said latter valve, and means to cause one agency to open the valve only when unopposed by the other agency.

6. In an automobile heating system, in combination, an automotive engine comprising an intake manifold and an exhaust line, a steam generator heated by said line, a steam radiator supplied with steam by said generator, a valve controlling means having connection with said intake 65 manifold and adapted to establish a vacuum in said system, means responsive to heat in said generator to close said valve when the system is hot, a valve and means controlled thereby to supply water to said generator, a thermostat responsive to exhaust line heat and means controlled thereby tending to open said water valve when the generator is hot, a thermostat responsive to the presence of steam in the system, and means controlled thereby which is effective to close said 70 75

water valve when the system is supplied with steam.

7. An automobile heater system according to claim 6, in which the water valve controls comprise each a thermal bulb and a bellows in closed circuit therewith filled with an expansible medium, and a water valve arm oppositely acted upon by said two bellows, the valve opening bulb being disposed to become heated in advance of the other bulb.

8. An automobile heater system according to claim 6, in which the water valve control means comprise two agencies each a thermal bulb and a bellows in closed circuit therewith filled with an expansible medium, a water valve arm oppositely acted upon by said two bellows, the valve opening bulb being disposed to become heated in advance of the other bulb, and a like bulb and bellows disposed and adapted to close said vacuum valve when the exhaust line is hot.

9. An automobile heating system according to claim 5, in which the heat responsive agency to open the water supply valve is a thermal bulb mounted adjacent to the steam generator and a bellows in closed circuit therewith filled with an expansible medium, an actuator for the water valve movable by said bellows, and an adjustable resistance to oppose the valve opening motion of said actuator.

10. An automobile heating system according to claim 5, in which the heat responsive agency to close the water supply valve is a thermal bulb mounted adjacent to the steam radiator and a bellows in closed circuit therewith filled with an expansible medium, an actuator for the water valve movable by said bellows and more powerful than the other valve controlling agency, and a stop to limit the valve travel.

11. An automobile heating system according to claim 5, in which the heat responsive agency to close the water supply valve is a thermal bulb mounted adjacent to the steam radiator and a bellows in closed circuit therewith filled with an expansible medium, an actuator for the water valve movable by said bellows and more powerful than the other valve controlling agency, a motor driven fan associated with said radiator, and means controlled by the expansion of said bellows for cutting said motor into service.

12. In an automobile heating system, means to generate steam, an automotive exhaust line to heat said means, means to supply water to said steam generating means comprising a valve and means responsive to the presence of steam in the heating system to close said valve, a steam radi-

ator heated by said generator, an electric motor driven fan associated with said radiator, a switch control for the fan motor, and a common means responsive to the presence of steam in said system which closes said motor switch as it closes said valve and vice versa, whereby said motor driven fan is cut into and out of service automatically.

13. An automobile heating system, comprising a steam generator heated by the engine exhaust, a steam radiator connected to said generator, a suction line and a water line connected to said generator, a valve for each line, a pair of bellows for operating said water valve, thermal bulbs each connected to one of said bellows and containing an expansible medium which will vaporize at a temperature below that of the water in the system, one bulb being responsive to heat at the generator and the other disposed to respond to the presence of steam in the system, an arm for operating the water valve oppositely acted upon by said bellows, a spring and stop acting to set the water valve in closed position when said bellows are substantially balanced, and an automatic control to close the suction valve while the system is in operation.

14. An automobile heating system according to claim 13, in which the automatic control for the suction valve comprises a bellows connected to the water valve controlling bulb that is responsive to the heat at the generator.

15. In a heating system, a heating conduit, a steam generator heated by said conduit, a steam radiator connected to said generator, valve control means to supply water to said system and counteracting agencies to control the water supply valve, one responsive to temperature of the heating conduit to open the valve and the other responsive to temperature in the system to close the valve.

16. In an automobile heating system, means to generate steam by engine exhaust heat, a radiator heated by steam so generated, a motor driven fan disposed to blow air heated by said radiator into the automobile, a valve controlling the supply of water to said steam generator, a control element for the fan motor, and a common means operable responsive to steam in said system to close said valve and start said fan motor.

17. An automobile heating system according to claim 16, in which said common means comprises a steam connection between the radiator and generator, and a thermostatic agency interposed in said connection.

JAMES B. MONCRIEF.
